PACK-OFF SHOE

Harry B. Boller, Alhambra, Calif., assignor, by mesne assignments, to Schlumberger Well Surveying Corporation, Houston, Tex., a corporation of Texas

Application March 25, 1954, Serial No. 418,650

16 Claims. (Cl. 166—100)

This invention relates to an improved pack-off shoe 15 for engaging the sidewall of a borehole and, more particularly, pertains to a pack-off shoe ideally suited for association with sidewall formation-fluid-sampling apparatus.

One type of formation sampler heretofore employed is provided with a pack-off shoe that is driven into engagement with the sidewall of a borehole at the depth of a formation to be sampled. The shoe is designed to seal a portion of the formation from the drilling fluid that usually fills the borehole, and thus fluid from the formation may flow via an entry port in the pack-off shoe to a sample-retaining chamber. After a desired amount of fluid is obtained, the sample-retaining chamber is closed, the shoe is retracted and the apparatus is withdrawn from the borehole so that the sample may be measured and analyzed.

While the operation of this formation sampler is generally satisfactory, in some instances the sidewall of the borehole under investigation may be so irregular that a good seal cannot be obtained. Consequently, the derived sample of formation fluid may be undesirably contaminated with drilling fluid.

It is, therefore, an object of the present invention to provide an improved pack-off shoe for engaging the sidewall of a borehole.

Another object of the present invention is to provide an improved pack-off shoe for a fluid sampler featuring a better seal between the formation to be tested and the borehole fluid than heretofore possible.

A pack-off shoe in accordance with the present invention comprises a support member movable between retracted and operative positions and a sheet-like sealing face of flexible material. The sealing face is provided with a fore portion and is connected at a plurality of peripheral points to the support member. In addition, the sealing face is arranged so that its fore portion is normally spaced from a reference plane defined by the support member in a direction toward the aforesaid operative position.

Thus, in association with a fluid sampler mechanism adapted to traverse a borehole, as the support member is displaced from a retracted toward an operative position, the sidewall of the borehole is engaged initially by the fore portion of the sealing face. Thereafter, drilling fluid is displaced from the space between the sidewall and the sealing face as additional portions thereof move toward and engage the sidewall, thereby to provide an effective seal.

The novel features of the present invention are set forth with particularity in the appended claims. The present invention, both as to its organization and manner of operation, together with further objects and advantages thereof, may best be understood by reference to the following description taken in connection with the accompanying drawings in which:

Fig. 1 is a perspective view of a complete sidewall fluid sampler incorporating a pack-off shoe embodying

2

the present invention and illustrating one portion of an operating cycle for the mechanism;

Fig. 2 is a cross sectional view taken along line 2—2 of Fig. 1 and drawn to an enlarged scale;

5 Fig. 3 is a side view of a portion of the apparatus of Fig. 1, drawn to the scale of Fig. 2, but illustrating another portion of an operating cycle, certain parts thereof being shown cut-away and in section to reveal various interior details;

10 Fig. 4 is a cross sectional view taken along line 4—4 of Fig. 3;

Fig. 5 is a view similar to that represented in Fig. 3, however, it illustrates yet another portion of an operating cycle for the mechanism;

Figs. 6 and 8 are cross sectional views taken generally along line x—x of Fig. 1, but illustrating respective, alternative pack-off shoe constructions embodying the present invention, shown in retracted positions; and

Figs. 7 and 9 represent the pack-off shoe arrangements of Figs. 6 and 8, respectively, in extended positions.

In Fig. 1 of the drawings, the fluid sampler incorporating a pack-off shoe embodying the present invention is shown disposed in a borehole 10 traversing earth formations 11, 12 and 13, and containing a drilling fluid 14, such as a water base or oil base mud. It is assumed that formation 12 is the one of interest from which a fluid sample is to be obtained.

The fluid sampler comprises upper and lower pressure-resistant housing sections 15 and 16 connected together in longitudinally spaced relation by a pair of side rails 17 and 18, which, as shown in Fig. 2, are transversely spaced from one another. The device 15, 16 is suspended in the borehole 10 by a cable 19 which, in connection with a winch (not shown) located at the surface of the earth, is employed to lower and to raise the device in the borehole in a customary manner.

In the vicinity of side rails 17 and 18, there is disposed a normally-retracted pad or pack-off shoe 20 embodying the present invention. Shoe 20 is of generally oval shape considering its projection on a plane parallel to the longitudinal axis of the fluid sampler, and comprises a sealing face 21 constructed of a sheet of flexible material such as rubber. It has a fore portion provided with a central insert 22 having upper and lower apertures

45 23 and 24, the functions of which will be described in detail hereinafter. Sealing face 21 is connected at a plurality of peripheral points to a generally oval-shaped, horizontally curved support ring 25. More specifically, the upper and lower portions of support ring 25 are somewhat forward of the side portions thereof and the support ring is suitably curved in each of the sections that connect its upper and lower portions with its side portions. The side portions of support ring 25 define a reference plane which is parallel to the longitudinal axis for device

55 15, 16. In the normally-retracted position of shoe 20, the central portion of face 21 containing insert 22 is spaced from this reference plane in a direction away from the longitudinal axis of the device. In other words, the distance along the surface of face 21 between any 60 pair of opposite points on ring 25 is longer than the straight-line distance between such points. Support member 25 preferably is of channel-like cross section and receives the entire peripheral edge of face 21.

As best shown in Fig. 3, a horizontally-curved driving plate 26 is welded, or otherwise peripherally connected, to support ring 25. It is provided with a central opening 27 through which a member to be later described, and a portion of insert 22 may pass and is connected to upper and lower driving pistons 28 and 29. Each of the pistons 28 and 29 is associated with one of hydraulic cylinders 30 and 31 of upper and lower cylinder housings 32 and 33 which are positioned between and secured to side

rails 17 and 18. The cylinders and pistons just described are oriented so as to impart transverse movement to driving plate 26 between a retracted and an operative position relative to the longitudinal axis of device 15, 16.

The housings 32 and 33 are further provided with hydraulic cylinders 34 and 35 which receive pistons 36 and 37, respectively. The latter pistons are connected to a horizontally-curved back-up pad or shoe 38 arranged for movement in a direction opposite to that of shoe 20.

Each of a pair of tension springs 39 and 40 is connected at its extremities to adjacent end portions of driving plate 26 and back-up shoe 38. They are arranged to bias the plate and the shoe toward one another and maintain them in normally-retracted positions shown in Figs. 1 and 2.

In order to permit the shoes 20 and 38 to attain relatively close, normally-retracted positions, driving plate 26 is provided with upper and lower openings 41 and 42 for receiving the rear portions of cylinders 34 and 35. Shoe 38 is similarly provided with openings 43 and 44 for receiving cylinders 30 and 31.

The cylinders 30, 31, 34 and 35 are fluidly connected to a hydraulic actuator (not shown) which may be disposed in upper housing section 15. This actuator may, for example, be of the type described in the copending application of Lawrence C. Chambers, filed April 7, 1950 and assigned the serial number 154,468, now Patent 2,674,313, for utilizing the pressure of borehole fluid 14 to drive pistons 28, 29, 36 and 37 in opposition to the bias of springs 39 and 40. Of course, any well-known system for imparting movement to plate 26 and to shoe 38 may be employed, such as a motor-driven screw-type jack.

To penetrate a desired formation and thereby facilitate the flow of formation fluid, the device is provided with a sample gun 45 supported within a channel 46 of a gun housing 47. Housing 47 is bolted or otherwise secured to insert 22 with a spacer 48 disposed therebetween. It is thus movable with the insert in a horizontal direction out of and into the space defined by side rails 17 and 18 and piston housings 32 and 33. In addition, since opening 27 is larger than the rear portion of insert 22 and spacer 48, these members are movable with respect to driving member 26.

Gun 45 contains a bullet 49 and has a barrel 50 aligned with port 24 in insert 22. A frangible plug or seal 51 normally blocks fluid communication between channel 46 and openings 52 and 53 in members 47 and 48 which are aligned with port 24.

Gun barrel 50 is provided with a plurality of radial openings 54 so that, as shown in Fig. 4, the interior of the barrel is in fluid communication with a channel 55 connecting channel 46 with a downwardly bent tube 56. The end of tube 56 is received by a flexible tube 57 which extends along rail 17, but is free to move so as not to inhibit movement of gun housing 47. The latter tube is connected to a sample-receiving chamber (not shown) in lower housing section 16. This chamber may be of any well-known construction, or may be of the type described in the aforementioned Chambers application, for obtaining a uniform, representative sample of formation fluid.

Inasmuch as the seal provided by face 21 may be so effective that shoe 20 cannot be retracted after a fluid sample is obtained, gun housing 47 is provided with a channel 58 that receives a get-away gun 59. The gun contains a bullet 60 and its barrel 61 is aligned with port 23 of insert 22, as well as with openings 62 and 63 in members 47 and 48. A frangible plug 64 normally blocks fluid communication between openings 58 and 62 and another frangible plug 65 in port 23 normally blocks fluid communication between the outer and inner surfaces of face 21 which may occur via port 23 and a connecting, vertically-extending channel 66.

This type of release mechanism is disclosed and claimed in the copending application of Clyde C. Chivens

and Roger Q. Fields, filed March 25, 1954, bearing the Serial No. 418,644, and assigned to the same assignee as the present application.

The various control circuits for the hydraulic actuator (not shown) of housing 15 and for the guns 45 and 59 are completed via insulated electrical conductors of cable 19. These circuits may be of any conventional arrangement or as arranged in the Chambers application.

In operation, housing 15, 16 is lowered in borehole 10 by means of cable 19 to a position wherein insert 22 is adjacent the formation to be tested; in this example, it is formation 12. Plugs 51 and 64 serve to prevent the entry of drilling fluid 14 into gun barrels 50 and 61 in this initial portion of an operating cycle.

Hydraulic fluid pressure is then applied to cylinders 30, 31, 34 and 35 so that pistons 28, 29, 36 and 37 are displaced to move driving plate 26 and back-up shoe 38 in opposition to the bias of springs 39 and 40 toward the sidewall of the borehole. As is evident from Fig. 2, since the sealing member 21 retains its shape as it is moved laterally and because of the configuration of shoe 20 the central, fore portion of sealing face 21 containing insert 22 will be the first to engage the sidewall. Thereafter, drilling fluid is displaced from the space between the sidewall and the sealing face as additional portions thereof move toward and engage the sidewall, while, at the same time, back-up shoe 38 engages the opposite section of the sidewall. Since the surface distance along sealing face 21 between any pair of opposite points on ring 26 is longer than the linear distance between such points, tangential forces are developed in the sealing face. That is, compressive or compactive lateral forces are developed in the sealing face which tend to reduce its surface area. Since the sealing face is made of rubber, forces transverse to the lateral forces are also developed and the face material tends to become thicker. Consequently, the outer surface of the sealing face is forcibly urged against the sidewall of borehole 10.

By reason of this constructional and operational feature, when the sampler is in the portion of an operating cycle illustrated in Fig. 3, the sealing face 21 engages and conforms very closely to a relatively large section of the sidewall. It thus provides a very effective fluid seal between the sidewall of borehole 10 and drilling fluid 14.

Of course, movement of insert 22 is accompanied by displacement of gun housing 47 and after shoes 20 and 38 are firmly positioned, gun 45 is fired to discharge bullet 49. The bullet ruptures frangible plug 51, passes through openings 52, 53 and 24 and comes to rest at a position in formation 12 designated in dash outline 49'. If the gas or oil contained in formation 12 is in producible form, it is under some pressure and may thus flow into the opening in the formation created by the bullet and into the sample-receiving chamber (not shown) of housing section 16 via a path including port 24, openings 53 and 52, gun barrel 50, radial openings 54, channels 46 and 55, and tubes 56 and 57. The fluid sample continues to flow into the sample chamber for an interval of time sufficient to permit entry of a desired quantity. Thereafter, the sample chamber is closed and the device is ready to be brought to the surface.

However, before housing 15, 16 may be raised, shoes 20 and 38 must be retracted. To this end, the hydraulic pressure on pistons 28, 29, 36 and 37 is reduced approximately to atmospheric pressure and the hydrostatic pressure of the mud 14 acting on the pistons via the shoes together with the bias of springs 39 and 40, displaces the shoes toward one another.

Because of the close conformity of sealing face 21 and the sidewall of the borehole, the sealing face may act as a suction cup. That is, this conformity plus the pressure of drilling fluid 14 on the rear surface of face 21 is such that the springs 39 and 40, although they retract driving plate 26 as shown in Fig. 5, are unable to draw

the face from engagement with the sidewall. In this event, get-away gun 59 is fired. Its bullet 60 ruptures frangible plugs 64 and 65 and opens a fluid path between the front and rear surfaces of the sealing face 21 via port 23 and channel 66, as shown in Fig. 5. The pressure differential between these surfaces is thus equalized and shoe 20 may be retracted.

Accordingly, with both shoes 20 and 38 retracted in the final phase of an operating cycle, the fluid sampler may be withdrawn from borehole 10. At the surface, the sample-receiving chamber (not shown) can be removed from housing section 15 and the sample therein analyzed.

In Fig. 6 there is shown another type of a pack-off shoe constructed in accordance with the present invention. Flexible face 21' is peripherally connected to a support ring 25', in turn, connected to a modified driving plate 26'. The driving plate has a flat central portion 76, rather than being curved, so that it may be driven close to a plate or backing member 71 disposed behind sealing face 21'. The plate 71 is curved to correspond to the retracted curvature of sealing face 21' and it is secured by a screw 72 passing through a central portion thereof to a modified central insert 22' which is somewhat longer than the insert 22 shown in Figs. 1-3.

This embodiment of the invention operates in essentially the same manner as the arrangement of Figs. 1-3. However, when back-up shoe 38' and driving plate 26' are driven toward respective sections of the sidewall of borehole 10, as shown in Fig. 7, the driving plate is displaced a greater distance than in the embodiment of Figs. 1-3. Greater tangential forces are thereby developed in sealing face 21', and these forces act to urge the sealing face toward the sidewall of the borehole. Thus, by providing means for mechanically producing tangential forces in the sealing face, an effective seal may be obtained with the sidewall of borehole 10.

Referring now to Fig. 8, the embodiment of the invention there shown comprises a central support 80 mounted to portion 16 of the principal housing. A channel-shaped member 81 is fixed to support 80 and, in turn, is rigidly secured to a curved plate 82. Plate 82 is generally similar to plate 71 of Figs. 6 and 7, but is coextensive with the entirety of sealing face 21''. It is secured by a screw 83 to an elongated central insert 22'' and is provided with a support ring 25'' about its periphery having a relatively deep channel 84 which receives the periphery of sealing face 21''. Thus, there is provided a support member having a curved portion 82 and terminating portions for the curved portion included in support ring 25''. Channel 84 of the support ring receives opposite points of the periphery of sealing face 21''. In the space defined by the channel 84 and the edge of sealing face 21'', there is disposed a resilient, expansible tube 85 sealed at one end (not shown) and fluidly connected to the hydraulic actuator (not shown) which drives the pistons of back-up shoe 38''. One of these pistons, designated 37'', is shown in Figs. 8 and 9.

In operation, back-up shoe 38'' is driven into engagement with a section of the sidewall of borehole 10 and the entire assembly, including the principal housing, supports 80 and 81, plate 82 and face 21'', thus is displaced toward the opposite section of the sidewall. Accordingly, insert 22'' of the sealing face 21'' engages the sidewall of the borehole and at the same time hydraulic pressure is applied to expansible tube 85. It is thus apparent that as drilling fluid is displaced from the space between the sealing face and the sidewall of the borehole, transverse expansion of tube 85 causes the peripheral edge of the sealing face to move relative to channel 84 and transverse forces are developed. In other words, in this embodiment of the invention, means are provided for selectively urging opposite points of the periphery of sealing face 21'' out of the channel portion 84 of support ring 25''. Because of such mechanically pro-

duced transverse forces in sealing face 21'', and due to the presence of plate 82, an effective seal may be obtained with the sidewall of borehole 10.

From the foregoing description, it is evident that a pack-off shoe constructed in accordance with the present invention provides a much more effective fluid seal than heretofore possible. Consequently, a fluid-sampling operation is greatly facilitated and the possibility of contaminating the sample with drilling fluid is minimized.

Although a pack-off shoe embodying the present invention has been illustrated in the environment of a fluid sampler, obviously it may be used in any other application wherein a fluid seal or a close association with the sidewall of the borehole is required.

While particular embodiments of the present invention have been shown and described, it is apparent that changes and modifications may be made without departing from this invention in its broader aspects, and therefore the aim in the appended claims is to cover all such changes and modifications as fall within the true spirit and scope of this invention.

I claim:

1. A pack-off shoe for use with a carrier adapted to be passed through a borehole comprising a support member selectively movable relative to the carrier between retracted and operative positions, and a sheet-like sealing element of flexible material connected substantially only at outer edge portions to said support member including a wall-engaging front surface and a rear surface, and including a substantially centrally located fore portion normally extending in a direction toward said operative position, said support having orifice means permitting any fluid in the borehole to communicate with said rear surface of said sealing element.

2. A pack-off shoe for a sidewall fluid sampler including a carrier adapted to be passed through a borehole, said shoe comprising a support member selectively movable relative to the carrier between retracted and operative positions, and a sheet-like sealing element of flexible material connected substantially only at outer edge

30 portions to said support member including a wall-engaging front surface and a rear surface, and including a substantially centrally located portion normally extending in a direction toward said operative position and having an opening, said support having orifice means permitting any fluid in the borehole to communicate with said rear surface of said sealing element, and said pack-off shoe further comprising a relative rigid member sealed to the periphery of said opening and movable with said centrally located portion, and means for selectively establishing a fluid communication path through said rigid member.

3. A pack-off shoe for use with a carrier adapted to be passed through a borehole comprising a support member movable relative to the carrier between retracted and operative positions, a sheet-like sealing element of flexible material including opposite edge portions connected to said support member including a wall-engaging front surface and a rear surface, and including a substantially centrally located fore portion normally extending in a direction toward said operative position, said support having orifice means permitting any fluid in the borehole to communicate with said rear surface of said sealing element, and a driving member mechanically connected to said support member and to the carrier and selectively operable to displace said support member between said retracted and said operative positions thereby to carry said sealing element toward the sidewall of a borehole.

4. A pack-off shoe for use with a carrier adapted to be passed through a borehole comprising a ring-like support member selectively movable relative to the carrier between retracted and operative positions, and a sheet-like sealing element of flexible material including a wall-engaging front surface and a rear surface, including a

70 75

periphery coextensive with and connected to said support member, and including a substantially centrally located fore portion normally extending in a direction toward said operative position, said support having orifice means permitting any fluid in the borehole to communicate with said rear surface of said sealing element.

5. A pack-off shoe for use with a carrier adapted to be passed through a borehole comprising a ring-like support member selectively movable relative to said carrier between retracted and operative positions, and a sheet-like sealing element of flexible material including a wall-engaging front surface and a rear surface, and including an edge coextensive with and connected to said support member, the distance along said front surface of said sealing element between any pair of opposite points on said ring-like support member being greater than the linear distance between such points thereby to provide a substantially centrally located fore portion for said sealing element spaced outwardly relative to a longitudinal axis for the carrier, said support member having orifice means permitting any fluid in the borehole to communicate with said rear surface of said sealing element.

6. A pack-off shoe for use with a carrier adapted to be passed through a borehole traversing earth formations comprising a support member selectively movable relative to the carrier between retracted and operative positions, a sheet-like sealing element of flexible material connected substantially only at outer edge portions to said support member including a wall-engaging front surface and a rear surface, and including a substantially centrally located fore portion normally extending in a direction toward said operative position, said support having orifice means permitting any fluid in the borehole to communicate with said rear surface of said sealing element, said pack-off shoe further comprising formation penetrating means connected to said fore portion of said sealing element for simultaneous movement therewith and movable relative to said support member.

7. A pack-off shoe for use with a carrier adapted to be passed through a borehole traversing earth formations comprising a ring-like support member selectively movable relative to the carrier between retracted and operative positions, a sheet-like sealing element of flexible material including a periphery coextensive with and connected to said support member, including a wall-engaging front surface and a rear surface, and including a substantially centrally located fore portion normally extending in a direction toward said operative position and having an opening, said support having orifice means permitting any fluid in the borehole to communicate with said rear surface of said sealing element, said pack-off shoe further comprising a closure for said opening in said fore portion, and explosively-operable means connected to said closure for simultaneous movement therewith and movable relative to said support member, said explosively-operable means being operative to establish a fluid passage through said closure and to penetrate an earth formation.

8. A pack-off shoe for use with a carrier adapted to be passed through a borehole comprising: a support member selectively movable relative to the carrier between retracted and operative positions and having orifice means; a sheet-like sealing element of flexible material connected to said support member including a wall-engaging front surface and including a rear surface communicable with any fluid in the borehole via said orifice means; and means for selectively producing laterally compressive forces in said sealing element thereby to urge at least a portion of said sealing element in a direction from said support member toward the sidewall of a borehole.

9. A pack-off shoe for use with a carrier adapted to be passed through a borehole comprising: a support member selectively movable relative to the carrier between retracted and operative positions and having orifice means; a sheet-like sealing element of flexible material connected

5 to said support member substantially only at outer edge portions and including a wall-engaging front surface and including a rear surface communicable with any fluid in the borehole via said orifice means; a backing member having a central portion adjacent a corresponding portion of said rear surface of said sealing element and having curved portions extending from said central portion toward said support member; and means for selectively driving said support member toward said curved portions 10 of said backing member to displace said sealing element toward the sidewall of a borehole, thereby to produce transverse forces in said sealing element and develop a buckling action therein which, due to the presence of said curved portion of said backing member, urges said front surface of said sealing element into sealing engagement with the sidewall of the borehole.

10. A pack-off shoe for use with a carrier adapted to be passed through a borehole comprising: a support member selectively movable relative to the carrier between retracted and operative positions and including a curved portion, a pair of terminating portions for said curved portion, and orifice means; a sheet-like sealing element of flexible material coextensive with said curved portion of said support member and having opposite edge portions thereof movably connected to said terminating portions, and said sealing element including a wall-engaging front surface and a rear surface communicable with any fluid in the borehole via said orifice means; means for selectively displacing said support member toward the sidewall of a borehole; and means for selectively displacing said opposite edge portions of said sealing element relative to said terminating portions of said support member thereby to develop transverse forces in said sealing element.

35 11. A pack-off shoe for use with a carrier adapted to be passed through a borehole comprising: a support member selectively movable relative to the carrier between retracted and operative positions and including a curved portion, a pair of channel portions terminating said curved portion, and orifice means; a sheet-like sealing element of flexible material coextensive with said curved portion of said support member and having opposite edge portions thereof received by respective ones of said channel portions, and said sealing element further including a wall-engaging front surface and a rear surface communicable with any fluid in the borehole via said orifice means; means for selectively displacing said support member toward the sidewall of a borehole; and means for selectively urging said opposite edge portions of said sealing element out of said channel portions of said support member thereby to develop transverse forces in said sealing element.

40 12. A pack-off shoe for use with a carrier adapted to be passed through a borehole comprising: a support member selectively movable relative to the carrier between retracted and operative positions and including a curved portion, a pair of channel portions terminating said curved portion and individually having an end wall, and orifice means; a sheet-like sealing element of flexible material coextensive with said curved portion of said support member and having opposite edge portions thereof received by respective ones of said channel portions, and said sealing element further including a wall-engaging front surface and a rear surface communicable with any fluid in the borehole via said orifice means; an expandible tube disposed between one of said edge portions of said sealing element and said end wall of the corresponding one of said channel portions; means for selectively displacing said support member toward the sidewall of a borehole; and means for selectively applying hydraulic pressure to said expandible tube to effect expansion of said tube thereby to urge said edges of said sealing element out of said channel portions of said support member and develop transverse forces in said sealing element.

45 75 13. A pack-off shoe for use with a carrier adapted to

be passed through a borehole comprising a support member selectively movable relative to the carrier between retracted and operative positions, and a relatively thin sealing element of flexible material connected substantially only at its edges to said support member and being of generally curved configuration to present a normally extended, substantially centrally located fore portion, and said sealing element further including a wall-engaging front surface and a rear surface, said support member having at least one opening whereby said rear surface of said sealing face may communicate with any fluid in the borehole.

14. A pack-off shoe for use with a carrier adapted to be passed through a borehole comprising a support member selectively movable relative to the carrier between retracted and operative positions, and a sheet-like sealing element of resilient material connected substantially only at its edges to said support member and being of generally curved configuration to present a normally extended, substantially centrally located, fore portion and said sealing element further including a wall-engaging front surface and a rear surface, said support member having at least one opening whereby said rear surface of said sealing element may communicate with any fluid in the borehole.

15. A pack-off shoe for use with a carrier adapted to be passed through a borehole comprising a support member selectively movable relative to the carrier between retracted and operative positions, and a sheet-like sealing

element of flexible material of generally curved configuration having a normally extended, substantially centrally located, fore portion, and side portions extending, at least in part, in the direction of movement of said support member and having edges connected to said support member, and said sealing element further including a wall-engaging front surface and a rear surface, said support member having at least one opening whereby said rear surface of said sealing element may communicate with any fluid in the borehole.

16. A pack-off shoe for use with a carrier adapted to be passed through a borehole, comprising a support member selectively movable relative to the carrier between retracted and operative positions, and a sheet-like sealing element of flexible material connected substantially only at outer edge portions to said support member including a wall-engaging front surface and a rear surface, and including a substantially centrally located fore portion normally extending in a direction toward said operative position, said pack-off shoe having passageway means therein to permit any fluid in the borehole to communicate with said rear surface of said sealing element.
